UNITED STATES PATENT OFFICE.

JULIUS WEIMAR, OF OFFENBACH-ON-THE-MAIN, GERMANY, ASSIGNOR TO
FABER & SCHLEICHER, OF SAME PLACE.

PRINTING-PRESS.

SPECIFICATION forming part of Letters Patent No. 559,423, dated May 5, 1896.

Application filed June 20, 1894. Serial No. 515,186. (No model.) Patented in Germany March 16, 1894, No. 78,272; in England May 9, 1894, No. 9,213; in France May 11, 1894, No. 238,442; in Belgium May 21, 1894, No. 110,109; in Italy June 26, 1894, No. 36,497; in Austria July 14, 1894, No. 44/3,230, and in Denmark July 27, 1895, No. 139.

To all whom it may concern:

Be it known that I, JULIUS WEIMAR, a subject of the Emperor of Germany, residing at Offenbach-on-the-Main, Germany, have invented certain new and useful Improvements 5 in Printing-Presses, (for which Letters Patent have been granted in England, No. 9,213, dated May 9, 1894; in France, No. 238,442, dated May 11, 1894; in Belgium, No. 110,109, 10 dated May 21, 1894; in Italy, No. 36,497, dated June 26, 1894; in Austria, No. 44/3,230, dated July 14, 1894; in Denmark, No. 139, dated July 27, 1895, and in Germany, No. 78,272, dated March 16, 1894,) of which the 15 following is a specification.

This invention relates to certain new and useful improvements in printing-presses; and it consists substantially in such features of construction, arrangement, and combinations 20 of parts as will hereinafter be more particularly described.

The invention has reference more particularly to what are known as "rapid" printing-presses, and it has for its object to increase 25 the working capacity of the press and to simplify the construction and arrangement of the impression-cylinder, as well as the devices or connections through the medium of which said cylinder is started and stopped at the 30 proper intervals.

The invention also has such other objects in view as will hereinafter more fully appear when taken in connection with the accompanying drawings, in which—

35 Figure 1 is a side elevation of a printing-press having my improvements embodied in connection therewith. Fig. 2 is a vertical transverse sectional view taken on the line $x-x$ of Fig. 1. Fig. 3 is a detached side view 40 in detail of the devices which are thrown into and out of engagement with the cam-groove, through the medium of which the impression-cylinder is actuated or started. Fig. 4 is a top or plan view of Fig. 3 in part horizontal 45 section.

50 My invention is capable of being practiced in several different ways; but preferably I resort to the use or employment of the devices substantially such as I have herein illustrated. Thus in the accompanying drawings

any suitable form of supporting-framework 1 is employed for the several operating parts of the machine, and the said framework is formed or provided longitudinally with guide-rails 2 2, in which the supporting guide-pulleys 3 3 for the reciprocating carriage y are received. The said carriage is formed or provided on its under side with suitable guide-flanges 5 5, which are adapted to the said pulleys 3, and also formed on the under side of said carriage, 60 at the central part thereof, is a suitable rack y' , which is engaged by a pinion x' , carried at the forward end of a connecting-rod w , the rearward end of which is eccentrically connected with the enlarged toothed wheel x at the point 65 x'' , the said toothed wheel x being engaged by a pinion t , carried by the main driving-shaft t' . The said pinion x' also engages and moves over a stationary rack v , and it will thus be seen in what manner the said carriage 70 y is operated or reciprocated back and forth.

To explain the operation, it may be stated, briefly, that the pinion t imparts motion to the enlarged toothed wheel x , and which latter, being eccentrically connected to the rod w , 75 causes the said rod to reciprocate, and which action moves or reciprocates the carriage in an obvious manner. The said carriage by being supported upon the guide-pulleys 3 3 is maintained in a straight line during the 80 movements thereof. The said carriage y receives and supports a table y' , upon which the engraved stone or type-form is suitably laid for the purpose of obtaining impressions therefrom, and it is of course obvious that 85 the said table and type-form is reciprocated or carried back and forth with the carriage as the latter is operated.

While I have herein described in detail the particular means by which the carriage is operated, it is apparent that any suitable conventional devices might be employed to the same end; but as I have found the present arrangement exceedingly simple and reliable I prefer the employment of the same in use. 90

The impression-cylinder a is suitably supported in bearings at the opposite sides of the framework of the machine, and in order to leave only as much surface as is required to obtain an impression I reduce the periphery 95 100.

of said roller or cut out a portion of the body thereof, which construction also permits of the satisfactory operation of suitable sheet-gripping devices which are employed, but which, however, are not herein shown or described. In lieu of any special form of such latter devices, any of the well-known or conventional forms of gripping devices are equally adapted to be used with my construction of impression-cylinder. The said impression-cylinder *a* has attached or secured thereto at one end a toothed wheel or pinion *b*, and the said wheel is provided with a steel tooth *l*, the normal position of which coincides with a vertical line drawn through the axis of the impression-cylinder and the function or purpose of which tooth will be more specifically referred to hereinafter.

Suitably supported in bearings at a point beneath the impression-cylinder and at that side of the machine at which the toothed wheel *b* is located is a suitable short spindle or shaft *r*, upon which is held or supported, in a manner to turn, a vertically-disposed lever *c*, the upper end of the said lever being notched at *c'*, so as to be engaged by the tooth *l*, as will be explained. The said lever *c* is formed or provided on its inner side at or near each end thereof with a lug or projection *c*², which lugs or projections fit into or enter corresponding notches or openings *c*³, formed at corresponding points in the vertically-disposed arms *d'* of a three-armed lever *d*, the third arm of said lever *d* being indicated at *d*³ and projecting forwardly and upwardly at an angle of about forty-five degrees, (45°.) The said lever *d* is formed with or attached to a hub *D*, which is movable longitudinally on the shaft or spindle *r*, and the hub is provided with a groove *D'*, in which is received the pins or lugs *s*, carried by the forked or bifurcated end *f* of a swinging lever *f'*, which is provided with a hub *f*² and has its bearing or point of oscillation on a stud or pin *f*³, suitably secured in place upon the framework. The opposite end of said swinging or oscillating lever *f'* is provided with a projection *g*³, which enters the cam-groove *g*⁴ of a cam or eccentric *g*, which latter has its bearing upon the shaft *g'*, the same as does the enlarged toothed wheel *x*, hereinbefore referred to. The arm *d*³ of the lever *d* is provided at its end with a pin *a'*, which supports a roller *a*² on each side of said lever-arm, and accordingly as the levers *c* and *d* are in or out of the proper positions to actuate and stop the impression-cylinder one of said rollers *a*² will be in engagement with a cam-groove *e* and the other will be received by a slot in a bridge *d*⁵.

The construction and relation which the levers *c* and *d* bear to each other is such that they are never disengaged from each other; but are always in a position to operate jointly or in unison, as will appear. The cam-groove referred to and shown is formed in a pendent portion constituting practically a

part of the carriage *y*, and the general shape of the same is such that when the carriage is at its rearmost position the horizontal or straight portions thereof will be on opposite sides of the said levers *c* and *d*. Also formed with the said carriage on its upper edge at the side corresponding to the toothed wheel *b* is a rack *b*², which engages said toothed wheel immediately the latter has been actuated or started, as about to be explained. When the carriage *y* has arrived at the end of its return stroke, or when the same is in the position indicated at Fig. 1 and is about to be sent forward again, the eccentric *g*, acting upon the lever *f'*, moves the three-armed lever *d* into such position that the inner one of the rollers *a*², carried at the end of the arm *d*³ thereof, will be carried into the forward end of the cam-groove *e*, and then as the carriage starts forward through the medium of the operating mechanism described, the said lever *d* will be brought forward on its axis *r*, the arm *d*³ being first thrown downward by reason of the shape and direction of the cam-groove, and the lever *c* being also rocked forward by virtue of the described connection of this lever with the said lever *d*. As the carriage *y* continues to move forward the said levers *c* and *d* will be gradually restored to their original position by virtue of the intermediate inclined portion *E* of the cam-groove, so that by the time the carriage has reached the limit of its forward movement and the roller *a*² of the third arm of the lever *d* is carried into the straight portion *E'* of the cam-groove the said lever *d* will be in readiness to be moved or shifted on the spindle *r*, so as to be carried out of engagement with the cam-groove. The engagement is broken at about the time the carriage reaches the end of its forward movement, and on the return movement of the carriage the cam-groove has no effect upon the levers. When the arm *d*³ of the lever *d* is thrown downward by the operation above described, the connection of the upper end of the lever *c* with the tooth *l* of the toothed wheel *b* gives to the impression-roller an impetus or initial start, and said wheel *b* becomes immediately engaged by the upper rack *b*², and the impression-cylinder is carried around and over the stone or type-surface, in an obvious manner.

I may employ any suitable devices for feeding the sheets to be printed upon to the impression-cylinder, as well as any preferred form of devices for gripping or taking hold of the sheets and holding them in position while being carried around by the impression-cylinder; but I have preferably omitted any such devices herein. In like manner I may employ any preferred or conventional form of inking rollers or devices, together with distributing and moistening devices; but have also purposely omitted to show such devices herein. It will be observed that the desired action of the impression-roller is obtained through the medium of devices which are ex-

ceedingly simple in construction and arrangement, and it will also be seen that the action of said devices is at all times perfectly reliable.

5 Located above the impression-cylinder a set of delivery devices for the sheets is employed; but inasmuch as the same forms no part of my present invention, and could be substituted for any of the approved conventional forms of such devices, no specific mention thereto need herein be made.

Without limiting myself to the precise details of construction and arrangement shown and described, I claim as my invention—

15 1. In a printing-press the combination with the impression-roller having the pinion provided with the lateral tooth the lever *c* in movable connection with said tooth, the three-armed lever *d* movably connected with said lever *c*, a reciprocating carriage having a rack engaging the pinion of the cylinder and provided with a cam-groove, and means for shifting the said lever *d* into and out of engagement with said groove at the completion of 20 the forward and return movements of said carriage respectively, substantially as described.

2. In a printing-press the combination of the reduced impression-cylinder provided with the pinion having the lateral tooth, the lever *c* vertically disposed and in movable connection with said tooth, the lever *d* in movable connection with said lever *c* and having the forwardly-projecting inclined arm carrying a roller, a reciprocating carriage 35 having a rack engaging the pinion and provided with a cam-groove, and means for shifting the lever *d* into engagement with said cam-groove at the limit of each return movement of the carriage, substantially as de- 40 scribed.

3. In a printing-press, the combination of the impression-cylinder provided with the pinion carrying the lateral tooth, the vertically-disposed lever *c* notched at its upper 45 end to engage said tooth and having the lugs on its inner side, the three-armed lever *d* having its vertical arms notched to movably en-

gage said lugs, and having its forwardly-inclined arm provided with a roller, a reciprocating carriage having a rack engaging the pinion and provided with a cam-groove in which the roller works, and means for shifting the lever *d* into engagement with said cam-groove at the limit of each return movement of the carriage, substantially as de- 55 scribed.

4. In a printing-press, the combination of the impression-cylinder provided with the pinion having the lateral tooth, the lever *c* constructed at its upper end to movably engage said tooth and having the lugs on its inner side, the three-armed lever *d* having its vertical arms notched to movably engage said lugs, the reciprocating carriage having the cam grooved and operating said lever *d*, the 60 movable bearing, the pivoted lever *f* furcated at its forward end to embrace said bearing, and the eccentric *g* having the cam-groove, the said latter-named devices operating to shift the lever *d*, substantially in the manner 65 70 and for the purpose shown and described.

5. In a printing-press, the combination with the impression-cylinder provided with the pinion having the lateral tooth, of the lever *c* in movable connection with said tooth and 75 having the lugs on its inner side, the three-armed lever *d* having notches in movable connection with said lugs, a reciprocating carriage, means on the carriage for throwing the levers forward on their axes and gradually restoring them to normal position, and means for shifting said lever *d* into and out of operative engagement on the completion 80 of the forward and return movements respectively of said carriage, substantially as de- 85 scribed.

In testimony whereof I have signed my name to this specification in the presence of two subscribing witnesses.

JULIUS WEIMAR.
